UNITED STATES PATENT OFFICE.

JAMES MUIRHEAD, OF PAWTUCKET, RHODE ISLAND.

WATER-HEATER AND STEAM-GENERATOR.

1,012,895.

Specification of Letters Patent. Patented Dec. 26, 1911.

Application filed June 23, 1910. Serial No. 568,580.

To all whom it may concern:

Be it known that I, JAMES MUIRHEAD, of Pawtucket, in the county of Providence, and in the State of Rhode Island, have invented 5 a certain new and useful Improvement in Water-Heaters and Steam-Generators, and do hereby declare that the following is a full, clear, and exact description thereof.

The object of my invention is to provide 10 a water heater and steam generator of the type in which the water is passed through a spiral course, in which the heat generated shall be utilized to the highest efficiency and which will enable access to the water pass- 15 sages for the perfect and easy removal of sediment, or other obstructions, therefrom; and to this end my invention consists in the apparatus constructed substantially as hereinafter specified and claimed.

20 In the drawings; Figure 1 is a vertical section of an apparatus embodying my invention; and Fig. 2 is a horizontal section on the line 2—2 of Fig. 1.

In the embodiment of my invention shown 25 in the drawings, the heat is supplied from a series of gas burners 10, each of which projects through an opening in the side of a casing 11, which is completely closed so as to have no communication with the external 30 air, so that it is air-tight and all air is ex- cluded except through the air-mixing burner. Thus, there is no undue draft through the casing which results in heat being car- 35 ried up through the chimney before it is fully utilized. Within the casing is a ver- tical series of heating members or units each composed of two disks, one 12, which has in its surface a tortuous passage or channel 40 13 of spiral form that is formed by a shal- low groove that has a flat bottom, the outer end of the spiral being in communication with a water inlet pipe 14 and the inner end of the spiral being in communication with a water outlet pipe 15. The other disk 45 16 is simply a flat plate applied to the open side of the groove 13, so as to complete the four sides of the groove, and the two plates are detachably connected together, as by screws or bolts 17, so that the cover plate 16 50 can be removed whenever desired to give

access to the groove 13 for the removal of sediment, etc. Obviously the construction is an inexpensive one, since only one disk need be provided with the spiral groove, the other being a simple plate with plane sur- 55 faces. Yet by reason of the flat form of the channel, a film of water of adequate extent is subjected to heat at top and bottom and at both sides, so that the raising of the water to the desired temperature is quickly and, 60 therefore, economically effected. There are no holes vertically through the two combined plates 12 and 16 of a unit, and thus no heat is lost by passing directly through a unit from top to bottom, and the only ver- 65 tical passage-way for the heat is between the circumference of each unit and the side of the water jacket.

The spiral groove instead of being of the form shown in Fig. 2, may be a regular 70 spiral of ordinary form.

An important characteristic of my appa- ratus is the absence of such conditions with- 75 in the casing 11 as result in back-draft, or the precipitation of moisture and the falling of drops of water on to the gas burners extin- quishing the light, or impairing the ef- ficiency of the burners.

What I claim is—

1. In an apparatus of the class described, 80 a water heating unit comprising abutting plates having inlet and outlet openings, and between which is a water passage of the form of a continuous spiral extending be- 85 tween said inlet and said outlet and consist- ing of a shallow channel whose walls are formed by the surfaces of the plates.

2. In an apparatus of the class described, 90 a water heating unit comprising abutting plates having inlet and outlet openings, and between which is a water passage of the form of a continuous spiral extending be- 95 tween said inlet and said outlet, and consist- ing of a shallow groove formed wholly in one of the plates in the side next to a con- tiguous plate, the open side of said groove being closed by the surface of said con- tiguous plate, and means separably connect- ing said plates.

3. In an apparatus of the class described, 100

the combination of an air-tight shell having an inlet for the water and an outlet for water or steam, a series of heating units assembled in the shell in communication with the inlet and the outlet, and means to connect the units as a series to one another, a series of gas burners for the respective units supported exterior to the shell and extend-

ing within the same contiguous to the respective units.

In testimony that I claim the foregoing I have hereunto set my hand. 10

JAMES MUIRHEAD.
